UNITED STATES PATENT OFFICE.

EDWARD H. BROOMHALL, OF HARRISBURG, PENNSYLVANIA.

CARD CASE.

Application filed November 27, 1925, Serial No. 71,802.

My invention relates to covers for cards, and more particularly to covers into which receipts, bills or bank notes and other such articles may be deposited. It has among 5 its many objects:—

One object is to provide a cheap and convenient combination card case, with means therein for holding the contents therein, and at the same time permitting the same to be 10 partially or wholly removed therefrom.

Another object is to provide a neat, durable cover that will hold its contents secure therein, and which may be replenished from time to time as may be necessary. And a 15 means for holding secure any memos or other papers that may be placed under the retaining band.

With the foregoing and other objects in view, further objects and advantages will 20 appear as the description of the invention is hereinafter developed.

Referring to the drawing wherein is shown what is now considered to be the preferred form of my invention:—

25 Fig. 1 is a perspective of the cover in an open position to show the construction and arrangements of the same before cards are placed therein; and

Fig. 2 is a side view of the cover or card 30 retainer.

My card case consists of any flexible material, preferably a leather oblong, section 3, that has its ends turned in, as shown at 4, so as to form a binding for the outer edges 35 5, and then is folded over at 6 upon itself, so as to form a top 7 and a bottom cover 8. The length of the top and bottom covers are of such length as to fit a predetermined size 40 card and at the same time to accommodate a folder bank note or other memorandum that may be placed therein.

To the bottom cover I prefer to suitably secure by one or more rivets, 9, a separate section 10 which is of such length when 45 placed in position as to have the end 11 extend a distance on the lower cover, and its free end 12 extend beyond the rivets 9 so as to fold over when the cover 7 is closed upon the contents.

50 Various means have been employed for holding contents permanently and temporarily within the binding covers, but in my device it is desired to have an elastic covered braid band 13 extend around the separate section 10 and having its ends secured to the separate section 10 by a suitable wire staple

or other means that will readily hold the two parts together and prevent displacement when the band 13 is lifted to place cards or other matter thereunder. By this 60 means the contents under the band 13 is held secure to the separate section 10 and is wholly free from the cover; in other words, the contents held by the separate section 10 and the elastic band 13 is free from the bottom 65 and top covers 8 and 7 respectively, and are only kept within the cover by reason of the rivets 9.

By constructing a cheap, readily convenient means for holding any contents that 70 you desire to preserve for ready reference, my cover will permit the insertion and removal without inconvenience or injury to the contents.

Another object of my invention is to provide a holder into which a suitable quantity 75 of loose leaves may be placed and securely held in position for writing upon, while at the same time any or all of said leaves may be easily removed and replaced by others. 80

From the foregoing description, taken in connection with the accompanying drawing, the construction, mode of operation, methods and advantages of my invention will be readily apparent, it is thought, without going 85 into various other details of its uses.

In accordance with the provision of the patent statutes, I have herein described the principal form of my invention which I now consider to represent the best embodiment 90 thereof; but I desire to have it understood that the invention can be carried out in other ways than that shown and described; for instance, in lieu of an elastic braided band, a spring such as a coiled spring flattened 95 and secured, the separate section would act as well, and accomplish every purpose that the elastic braided band does. But all are intended to come within the scope of the claim. While my binder or cover may be 100 used as a card case, it is equally adapted for a loose leaf binder and for other purposes.

Having thus described my invention, what I claim as new, and desire to protect by Letters Patent, is:—

105 A card case comprising two sheets of material of unequal lengths and foldable one within the other, the inner sheet being folded to provide sections of unequal lengths, and the outer sheet being folded to provide sections of substantially equal lengths, the longer section of the inner sheet being per-

manently attached to the adjacent section of the outer sheet, an inherently resilient band retained between the longer end of the inner sheet and the adjacent portion of the outer sheet and extending over the long end of the inner sheet at a point adjacent to but not engaging the terminal of the short end of the inner sheet to receive and retain a

body of cards thereon, and the folded portions of the inner sheet constituting the 10 container for the cards, and the folded portions of the outer sheet constituting the cover for the container and cards.

In testimony whereof he affixes his signature.

EDWARD H. BROOMHALL.
